UNITED STATES PATENT OFFICE.

FREDERICK KOHNLE, OF DAYTON, OHIO, ASSIGNOR, BY MESNE ASSIGNMENTS, TO THE MONARCH TAG COMPANY, A CORPORATION OF OHIO.

PRICE-TAG.

1,194,508.

Specification of Letters Patent. Patented Aug. 15, 1916.

Application filed March 11, 1912. Serial No. 683,161.

To all whom it may concern:

Be it known that I, FREDERICK KOHNLE, a citizen of the United States, residing at Dayton, in the county of Montgomery and 5 State of Ohio, have invented certain new and useful Improvements in Price-Tags, of which the following is a specification.

My invention relates to a new article of manufacture comprising a continuous series 10 of price tags for merchandise, the fastening means for securing the tags to the merchandise being pre-affixed to the strip at regular intervals.

The object of the invention is to produce 15 these strips as an article of commerce adapted to be utilized in connection with a stamping machine for severing and marking the strip into independent tags.

The features of the invention are more 20 fully set forth in the description of the accompanying drawing, forming a part of this application, in which:

Figure 1 is a plan view of the strip showing one of the units severed. Fig. 2 is a 25 plan view of one of the units of the strip unfolded, and showing the manner of attaching the cord. Fig. 3 is a side elevation of the folded strip showing the cord in section.

30 1 represents the strip of paper of a suitable length to comprise a selected number of tag units. This strip consists of a paper tape folded upon itself, as shown in Fig. 3.

2 represents the fold edge of the strip, 35 provided at regular intervals with marginal divisional cuts 3 disposed at regular intervals and terminating near the medial line of the strip, the terminating ends being in alinement.

40 4 represents a series of orifices in the folded edge of the strip midway between the divisional cuts.

The preferred manner of attaching the 45 loops is as follows: The strip is first in its unfolded condition, as indicated in Fig. 2.

A continuous cord is extended along the medial line of the unfolded strip and at intervals the loops 5 are drawn through the orifices 4, the straight portion of the cord

being concealed within the fold when the strip is folded upon itself, the meeting faces being glued together and securing between them the base or anchoring end of the cord 6. When a gang is operated upon by the appropriate machine, the loops 5 extend upon one side of the cutter and the cutter operates to continue the divisional cuts 3 and sever the strip into suitable units, the divisional cuts also being functional in enabling the appropriate step feed. The 60 machine is supposed to sever and mark the tags which may then be attached to the articles to be identified by simply passing the tag through its loop and catching some convenient portion of the article into the 65 slip-noose thus formed. This is very simple, cheap and convenient, requiring very simple forming and operating means, the gangs make convenient articles of commerce and the severed units can be readily attached to the article to be identified. The 70 divisional cuts sever the continuous cord at the edges of the tag lengths, which dispose the ends of each loop parallel with the folded edge of the tag, securing the ends at 75 right angles to the pulling strain of the looped portion of the cord, resisting any withdrawal tendency of the ends from the tag.

Having described my invention, I claim:— 80
A new article of manufacture comprising a tape folded upon itself with the fold edge extended longitudinally and the laps of the fold adhesively united forming a continuous tag strip longitudinally partially divided 85 by parallel notches, adapted to coöperate with feeding devices into a plurality of tag widths, the notches extending from the fold edge inwardly, and a cord secured between the fold edge and projecting through a 90 notch medial of each tag width.

In testimony whereof, I have hereunto set my hand.

FREDERICK KOHNLE.
